[57] CLAIM

The ornamental design for a vehicular telephone set or similar article, as shown and described.

DESCRIPTION

FIG. 1 is a front elevation illustrating a vehicular telephone set or similar article showing our new design;

FIG. 2 is a rear view thereof;

FIG. 3 is a top plan view thereof;

FIG. 4 is a bottom plan view thereof;

FIG. 5 is a side elevational view from the left thereof;

FIG. 6 is a side elevational view from the right thereof;

FIG. 7 is a front perspective view thereof;

FIG. 8 is a front perspective view thereof in which a hand set is taken off;

FIG. 9 is a front perspective view of the set mounted on a vehicle dash; and

FIG. 10 is a front perspective view thereof, with the handset taken off.

The broken lines are shown for illustrative purposes only.
